brook, Tenafly, N. J., assignors to Raymond
Concrete Pile Company, New York, N. Y., a cor-
poration of New Jersey

Application April 16, 1943, Serial No. 483,246

14 Claims. (Cl. 114—65)

This invention relates to vessels, either self-propelled or towed, and to methods of making them. More specifically, it relates to such vessels composed of concrete and steel and to methods of constructing and assembling them.

The invention has for its objects, among others, to provide an economical method of constructing reinforced concrete vessels. It makes possible the working of the steel at higher unit stresses, which in turn reduces the required amount of steel, and provides a method of forming and casting the concrete which is more economical than the usual methods. As is well known in the art of making reinforced concrete, the concrete surrounding the steel shrinks while it is setting, which shrinkage places the steel under compression. In consequence, before the steel can take its tension load the concrete is subjected to a tension force caused by its bond with the steel. This results in limiting the working stress to not more than 12,000—15,000 pounds per square inch, and sometimes less. If greater stresses are used there is danger of disrupting the concrete to a degree that permits water and air to disintegrate the steel.

As against this, if the steel is put in tension and is released to a degree that will continually keep the concrete in compression and hold the compression after the concrete is set, the two materials work together in a manner that permits the steel to be loaded to its full safe working tension without any disruptive action on the concrete. This makes it possible to work the steel to materially higher unit stresses and thereby save in quantity of steel used.

Furthermore, by making the vessel structure in sections so that they can be poured in vertical forms which can be used without complete dismantling and in which the reinforcing steel can be stressed before the concrete is poured, it is possible to save substantially in material, labor and time. Other objects and advantages will appear as the disclosure proceeds.

Referring to the drawings which illustrate, to some extent diagrammatically, what we now consider to be a preferred form of the invention.

Fig. 1 is an elevation, partly broken away, of a ship constructed in accordance with our invention;

Fig. 2 is a plan view, partly broken away, of the ship shown in Fig. 1;

Fig. 3 is a sectional elevation, taken on the line 3—3 of Fig. 4, showing one of the intermediate or waist sections of the ship in cross-section;

and showing a part of the apparatus employed in assembling a number of such sections;

Fig. 4 is an elevation, partly broken away, of one form of apparatus employed in practicing the invention;

Fig. 5 is a detail view, partly in section, of apparatus for taking up slack and for a purpose hereinafter appearing;

Fig. 6 is a section taken on the line 6—6 of Fig. 5;

Fig. 7 is a longitudinal section taken on the broken line 7—7 of Fig. 3;

Fig. 8 is an enlarged detail longitudinal section showing a part of a joint and bulkhead or partition between adjacent sections shown in Fig. 7.

It is well known that a ship at sea is often subjected to severe stresses. It is at times supported by a wave at the mid-section of its waist, similar to a beam supported at its middle, and alternately, by a wave at or near the bow and a wave at or near the stern. It must be designed and constructed to withstand the consequent severe strains without developing objectionable leaks.

One of the approved methods of building ships of reinforced concrete is to cast the concrete in longitudinally continuous pourings, but this is a difficult, complicated, expensive and otherwise objectionable procedure. The use of precast sections provides a cheaper method of manufacture, but it has been, heretofore, difficult, if not impossible, to provide a joint between the sections that is leak-proof and otherwise satisfactory.

According to our invention, the ship is composed of a bow section 10, a stern section 12, and a plurality of waist sections 14 between the bow and stern sections. In the drawings the ship propulsion apparatus and other necessary machinery are located in the stern section 12, and the usual auxiliary apparatus is located in the bow section 10; and the intermediate or waist sections 14 primarily constitute the cargo carrying space. Each of the sections 14 is composed of concrete, reinforced with steel, the longitudinally extending reinforcing rods or members being pre-stressed. By "pre-stressed" we mean that the steel has been placed in tension prior to pouring of the concrete and maintained under such tension during pouring and until the concrete is able to take compression. The applied tension is such (when released) as to place the set concrete in substantial crack-preventing, longitudinal compression. The reinforced concrete bow (10) and stern (12) sections may be constructed in the common or usual way or the steel of either

or both of them may also be pre-stressed. After individual sections have been constructed they are assembled and joined by welding or otherwise firmly fastening together the reinforcing longitudinal rods so that such joints as need to be pre-stressed can be so built.

Each of the waist or intermediate sections 14 may be shaped in cross-section as shown in Fig. 3. The two cylindrical portions are substantially tangent to each other and integrally connected at their point or zone of tangency 18. The cylindrical portions 16 are also integrally connected with upper and lower arches 20, 20. As stated, the material 16-18-20 is concrete suitably reinforced transversely and longitudinally. Reinforcing members are not shown in Fig. 3 but longitudinal reinforcing members are shown in others of the drawings. It is with the longitudinally (fore to aft) extending reinforcing members that we are chiefly concerned and we shall confine our disclosure to them.

Each of the sections 14 has a plurality of pre-stressed reinforcing rods 22 (see Figs. 5 and 8). Each rod 22 extends preferably continuously longitudinally through the wall of its particular section 14 and extends beyond the latter at each end. Each rod is shown screw-threaded at its opposite ends for a purpose presently appearing.

After the various sections 14 are constructed, they are assembled, connected and joined by the means and according to the method now to be described.

The sections 14 are mounted on planks or skids 24 which, in turn, are supported on a concrete bed or base 26 (Figs. 3 and 4). A plurality of gantries 28 are provided for supporting a plurality (in the present case, two) longitudinal cylinders 29 which act as compression members to transmit the load from two hydraulic rams 30 which react against the top of abutment 36. Similar hydraulic rams 32, 32 are provided between abutment 36 and bed 26. The bases of the ram cylinders abut or seat against the bed 26 which in turn, at the left hand end bears against a stiff (almost non-deflectable) abutment 34 of reinforced concrete. The plungers of each ram engage a similar abutment 36 that is bodily movable longitudinally; i. e., toward and away from the abutment 34. Each abutment 34, 36 has projecting steel rods 38 which are firmly embedded in the abutment and are the same in number as those in each section 14 and which are similarly located so as to be registrable therewith. Each rod 38 is screw-threaded at its projecting end.

In assembling the sections 14, the procedure is as follows. A yoke 40 (see Figs. 5 and 6) is slipped over the end of each rod 38 of the abutment 36 and a nut 42 is then screwed onto the end of each of those rods. A yoke 40 is slipped over the end of each rod 22 that projects toward the left from each of the sections 14, and a nut 42 is screwed onto the ends of each of those rods. The rods 38, 22, 38, are aligned so as to be in longitudinal registration. The yokes 40 are moved to the left on the rods which carry them, onto the adjacent rods 22 of the adjacent sections 14 or the rods 38 of the abutment 34. A nut 42 is screwed onto the end of each of the rods 38 of the abutment 34 and onto the end of each of the rods 22 which project to the right (Fig. 4) from the sections 14. Each of the nuts is constructed, as by knurling the periphery, so as to be turned by a suitable wrench or other tool.

The nuts 42 are turned to take up all slack 75

and so that the tension exerted upon the various longitudinally extending series of rods 22 shall be uniform when the abutment 36 is moved longitudinally, i. e., away from the abutment 34. Liquid under pressure is then supplied to the rams 30, 32 to apply uniform tension to the projecting ends of all of the rods 22 and to the yokes 40. The tension may be substantially the same as that previously applied to the rods 22 when casting each section 14, and so as to place the projecting ends of the rods 22 and the yokes 40 under a considerable tension, but below the elastic limit of the steel composing the rods 22 and yokes 40. This tension is now maintained on the system during the completion of the joints between the sections 14. Each such joint is then completed as follows.

Using suitable forms, concrete is poured between the end surfaces of the adjacent sections 14. Preferably, a pre-cast suitably reinforced concrete transverse partition or bulkhead 50 is placed in position (see Figs. 7 and 8) at each joint before the joint is poured. After the concrete poured to complete the joints between the sections 14 has set, the tension is released by relieving the pressure of the liquid in the rams 30, 32. The joints between the sections 14 are now complete and appear as shown in Figs. 7 and 8. Each of such joints, by virtue of the pre-stressed longitudinally extending ends of the rods 22 and yokes 40, is tight, substantially leak-proof, and comparatively light and not bulky. The partitions or bulkheads 50 aid materially in strengthening the structure.

The joint forms are removed through suitable hatch openings (not shown).

Each joint connecting the sections 14 has, in the space between cylinders 16 and arches 20, openings 52 to provide access from section to section after completion of the ship.

After the sections 14 have been joined as described above, the yokes 40 are disconnected from the rods 38 and the abutments 34 and 36 are moved out of the way so that the bow (10) and stern (12) sections may now be joined to the opposite ends of the completed waist 14, 14. This may be accomplished in a manner similar to that described above except that (at least in some cases) pre-stressing of the rods and their yokes 40 in the bow and stern joints may not be required since those joints are not subjected to the enormous stresses which the joints between sections 14 of the waist of the ship encounter.

A completed ship appears as shown in Figs. 1 and 2. While the invention is not limited to the number and dimensions of the particular sections employed, we give the following as one example. For a ship having an overall length of about 280 feet with a thirty-five foot beam, the bow section 10 would be fifty feet long, each of the waist or intermediate sections 14 would be twenty-five feet long, there being seven of such sections 14, and the stern section 12 would be fifty feet long. The size and distribution of the longitudinal reinforcing steel rods 22, and their corresponding yokes 40, in the cylindrical walls 16, 16, and in the arches 20, 20 (Fig. 3) will depend upon the size and class of ship desired.

In the particular ship illustrated, each section (see Fig. 3) embodies two substantially cylindrical members joined as above described. The invention however is not limited to the use of two such cylinders. For example, in some vessels

it may be desirable to use three of such cylinders side-by-side and suitably connected. The invention may also be applied to other shapes of ships.

The invention has been shown and described as applied to a ship, i. e., a self-propelled vessel. It is applicable, however, to barges or other vessels which are not self-propelled but are towed. It is therefore to be understood that the word "vessel," used in the appended claims, is meant to include vessels, whether they be of the self-propelled or towed type.

In accordance with the provisions of the patent statutes, we have herein described the principle of operation of our invention, together with the apparatus which we now consider to represent the best embodiments thereof, but we desire to have it understood that the apparatus disclosed is only illustrative and that the invention can be carried out by other means. Also, while it is designed to use the various features and elements in the combinations and relations described, some of these may be altered and others omitted, without interfering with the more general results outlined, and the invention extends to such use within the scope of the appended claims.

What we claim is:

1. A reinforced concrete vessel including, in combination, a bow section, a stern section, and a plurality of pre-cast waist sections intermediate said bow and stern sections, reinforced concrete joints connecting the bow and stern sections to their adjacent waist sections, and reinforced concrete joints connecting the waist sections, the reinforcement of said last mentioned joints including longitudinally extending pre-stressed steel members.

2. In a reinforced concrete vessel, in combination a plurality of pre-cast reinforced concrete waist sections having longitudinally extending steel reinforcing members extending through them and projecting from the opposite ends, the ends of the members of each section being connected to the ends of the members of an adjacent section, and concrete embedding the members between sections, the steel between adjacent sections being pre-stressed.

3. A reinforced concrete vessel including, in combination, a pre-cast bow section, a pre-cast stern section, a plurality of pre-cast waist sections intermediate said bow and stern sections, and a plurality of connected steel reinforcing members extending from the bow section to the stern section and pre-stressed between adjacent waist sections.

4. The method of constructing a reinforced concrete vessel, which method includes, in combination, pre-casting a plurality of waist sections each having longitudinally extending pre-stressed steel reinforcing members projecting from the opposite ends thereof, joining the ends of the members of one section to the ends of the members of an adjacent section, applying tension to the steel reinforcing members between adjacent sections, completing the joints between sections by covering the exposed members with concrete, and maintaining the applied tension until the concrete between sections has set.

5. A reinforced concrete vessel including, in combination, a bow section, a stern section, and a plurality of pre-cast waist sections intermediate said bow and stern sections, each of said waist sections having pre-stressed longitudinal reinforcing members, reinforced concrete joints

connecting the bow and stern sections to their adjacent waist sections, and reinforced concrete joints connecting the waist sections, the reinforcement of said last mentioned joints including longitudinally extending pre-stressed steel members.

6. In a reinforced concrete vessel, in combination, a plurality of pre-cast reinforced concrete waist sections having longitudinally extending steel reinforcing members, means connecting the ends of the members of each section to the ends of the members of an adjacent section, and concrete embedding the members between sections, the steel between adjacent sections being pre-stressed.

7. A reinforced concrete vessel including, in combination, a pre-cast bow section, a pre-cast stern section, a plurality of pre-cast waist sections intermediate said bow and stern sections, each of said waist sections having pre-stressed longitudinal reinforcing members, and a plurality of connected steel reinforcing members extending from the bow section to the stern section and pre-stressed between adjacent sections.

8. The method of constructing a reinforced concrete vessel, which method includes, in combination, pre-casting a plurality of waist sections each having longitudinally extending steel reinforcing members, joining the ends of the members of one section to the ends of the members of an adjacent section, applying tension to the steel reinforcing members between adjacent sections, completing the joints between sections by covering the exposed members with concrete, and maintaining the applied tension until the concrete between sections has set.

9. A reinforced concrete vessel including, in combination, a pre-cast bow section, a pre-cast stern section, and a plurality of pre-cast waist sections intermediate said bow and stern sections, the total length of said waist sections being greater than the sum of the lengths of the bow and stern sections, reinforced concrete joints connecting the bow and stern sections to their adjacent waist sections, and reinforced concrete joints connecting the waist sections, the reinforcement of said last mentioned joints including longitudinally extending pre-stressed steel members.

10. In a reinforced concrete vessel, in combination, a plurality of pre-cast reinforced concrete waist sections having longitudinally extending pre-stressed steel reinforcing members, means connecting the ends of the members of each section to the ends of the members of an adjacent section, and concrete embedding the members between sections, the steel between adjacent sections being pre-stressed.

11. A reinforced concrete vessel including, in combination, a pre-cast bow section, a pre-cast stern section, a plurality of tubular pre-cast waist sections intermediate said bow and stern sections, and a plurality of connected steel reinforcing members extending from the bow section to the stern section and pre-stressed between the ends of adjacent waist sections.

12. The method of constructing a reinforced concrete vessel, which method includes, in combination, pre-casting a plurality of waist sections each having longitudinally extending pre-stressed steel reinforcing members, joining the ends of the members of one section to the ends of the members of an adjacent section, applying tension to the steel reinforcing members between

adjacent sections, completing the joints between sections by covering the exposed members with concrete, and maintaining the applied tension until the concrete between sections has set.

13. A reinforced concrete vessel including, in combination, a bow section, a stern section, a plurality of pre-cast reinforced concrete waist sections having longitudinally extending steel reinforcing members, and reinforced concrete joints connecting the waist sections, the reinforcement of said last mentioned joints including longitudinally extending steel members in a state of tension, and the concrete in said joints being in a state of compression.

14. The method of constructing a reinforced concrete vessel, which method includes, in combination, pre-casting a plurality of waist sections each having longitudinally extending prestressed steel reinforcing members, joining the ends of the members of one section to the ends of the members of an adjacent section, and applying tension to the steel reinforcing members between adjacent sections while completing the joints between sections by covering the exposed members with concrete.

MAXWELL M. UPSON.
JOHN N. PHILBROOK.
